Attorney

UNITED STATES PATENT OFFICE.

GEORGE HORNECKER, OF ELMHURST, NEW YORK, ASSIGNOR TO L. R. CONWELL, OF ELMHURST, NEW YORK.

DISPLAY DEVICE.

Application filed July 21, 1924. Serial No. 727,157.

To all whom it may concern.

Be it known that I, GEORGE HORNECKER, a citizen of the United States, and a resident of Elmhurst, Queens County, New York, have invented a new and useful Improvement in Display Devices, of which the following is a specification.

This invention relates to display devices, and with regard to certain more specific features, to a representation of a pyramidal stack of cans, cartons, or other objects and the like, and a display support therefor.

Among the several objects of the invention may be noted the provision of a simple and inexpensive device for displaying the perspective likeness of a stack (or successive tiers) of objects and the like, together with suitable legends; and the provision of a strikingly attractive device of this type which can be made from two blanks and shipped flat. Other objects will be in part obvious and in part pointed out hereinafter.

The invention accordingly comprises the features of construction, combinations of elements, and arrangements of parts, which are exemplified in the constructions herein-after described and the scope of the application of which will be indicated in the following claims:

30 In the accompanying drawings, in which is shown one of various possible embodiments of this invention,

Fig. 1 is a plan view of the main supporting member laid flat;

35 Fig. 2 is a plan view of the central auxiliary display member laid flat;

Fig. 3 is a front elevation of the device in assembled display position;

40 Fig. 4 is a right side elevation of Fig. 3;

Fig. 5 is a top plan view of Fig. 3;

Fig. 6 is a plan view of the complete device folded for shipment;

Fig. 7 is an edge view of Fig. 6; and

Fig. 8 is a top plan view of a modification.

Similar reference characters indicate corresponding parts throughout the several views of the drawings.

Referring now more particularly to Fig. 1 of the accompanying drawings, there is illustrated at 1 a main support formed of a single sheet of suitable material such as patent coated manila. For a size such as $18\frac{1}{2} \times 44$ inches, a thickness of 25 points is suitable.

The device may take a variety of forms. In Figs. 1 to 4, its tiered members may be represented as being lithographed with representations of cans. These members may also carry suitable legends, and the objects represented may be varied in kind. The device is particularly well adapted to depicting articles in tiers, regular or otherwise.

In making the main support 1 shown in Fig. 1 only two operations are required, namely, lithographing or equivalent and die-cutting. The double dotted lines 3, 5, 7, 9, 11 and 13 indicate scoring to facilitate bending of the device from the flat or shipping form shown Figs. 1, 2, 6 and 7 to a display form shown in Figs. 3, 4 and 5. The double solid lines 15, 17, 19 and 20 indicate incisions or slotting for freeing certain portions from others and interlocking purposes as will be hereinafter described.

The scores 31 and 13 serve to bend the central portions of the display tiers forward for perspective effect, while the score 11 serves to bend the central portion of the intermediate portion rearwardly to facilitate interlocking with the central auxiliary member 33 shown in Fig. 2. The incisions 19 and 20 outline the upper and lower tier illustrations on one edge and relieve them for bending purposes.

The auxiliary second piece or member 33 comprises a sheet made of the same kind of material as the above-mentioned support 1. It may be lithographed and die cut by the same process. This member 33 comprises two sections 37 and 39 adapted to be folded forwardly at an angle with one another on the score 35. These sections 37 and 39 are notched by incisions 41 and 43 adapted to cooperate with the aforementioned incisions 15 and 17 of the support 1 said pairs of incisions being the same length.

The device is assembled for display by extending the lower tier 25 forwardly. This is done by bending on the score 13, also in the case of the upper tier by bending on the score 31. The central intermediate portion 29 is bent rearwardly on the score 11. The auxiliary device 33 is then bent forwardly on score 35.

The two bent devices are interlocked by means of the pairs of incisions 15, 17 and 41, 43, the auxiliary display 33 filling in the void left in support 1 caused when the in-

termediate section 29 was bent rearwardly (Fig. 5). The display section 33 now forms the central offset tier in the apparent stack, the upper display section 27 the upper rearward tier, and the lower display section 25 the forward lower tier (Fig. 4). The relative depths of the upper and lower tiers is governed by the length of slots forming them as illustrated in Figs. 1 and 5. The 10 number of central secondary display sections 33 to be inserted as section or tier members may be multiplied, depending upon the number of tiers required. Their 15 apparent size is governed in part by the positioning of their interlocking slots.

The side wings 21 and 23 may now be set at any desired angle, the preferred position being in line and parallel to one another.

20 By having the central portion of the device stand outside of the plane of the side wings, the central portion appears to be in space perspective with respect to the advertising or display material represented 25 on the said wings, thereby presenting a striking appearance to the observer.

In order to make the assembly of a permanent nature the hinges 45 and 47 made of paper, cloth or a like flexible-sheet 30 material are glued to the two portions of the device at the rear of the lower portions of the interlocking incisions 15, 41 and 17, 43. These hinges prevent the device from falling in two when picked up for folding, 35 prior to shipment or displacing, and yet permit its being completely folded as shown in Fig. 6.

It will be seen that no extraneous supports are required, and only a small amount 40 of gluing is required in the manufacture of the article. Expensive folding in manufacture is eliminated entirely.

The lower edge of the part 33, it will be noted, is on the same surface as the lower 45 edge of the support, and has likenesses of the objects illustrated or lithographed to said bottom edge of the part 33. Thus if the eye of an observer should be higher than the upper edge of the lower tier display 50 play the illusion of perspective would not be lost. Likewise, the upper tier display has its relieving slot 20 cut lower than the upper lever of the auxiliary piece 33 or central tier display, and is lithographed to 55 said slot for the same reason as stated above. The overlapping effect between the second and third tier need not be carried out so far however as between the first and second tiers because the observer's eye is 60 not at so great an elevation above this point as the previous one.

A preferred way of folding for shipment is shown in Figs. 6 and 7. The assembled device, on display, is grasped by the side 65 wings and they are drawn away from one

another. This action flattens out the assembled device in the manner of a pair of lazy-tongs when lengthened. The hinges flatten. Next the whole device is folded rearwardly on the central scores 31, 13 and 70 11. Then the side wings 21 and 23 are bent forwardly on the scores 3 and 5. The result is a flat folded position of the device which is about one-fourth the display size 75 in area. The flatness and compactness when folded are highly desirable features in shipping.

In Fig. 8 there is shown an alternative position for the tiers in which they appear to be stacked in round columns. This effect is obtained by scoring the tier pieces a multiple number of times, vertically along the outlines of the illustrations and then folding forward as heretofore described. The increased number of scores facilitates 85 bending to the more or less rounded contour.

In view of the above, it will be seen that the several objects of the invention are 90 achieved and other advantageous results 95 attained.

As many changes could be made in carrying out the above constructions without departing from the scope of the invention, it is intended that all matter contained in the 95 above description or shown in the accompanying drawings shall be interpreted as 100 illustrative and not in a limiting sense.

I claim:

1. An advertising device comprising a 100 one piece support; and a one piece second piece; said one piece support comprising a lower forwardly bent section, an upper forwardly bent section, side wings, and a bent central section joining all the aforesaid sections; said one-piece second piece comprising a forwardly bent flat section 105 adapted to interlock and hinge with said bent central section.

2. An advertising device comprising a 110 one piece support; and a one piece second piece; said one piece support comprising a lower forwardly bent section, an upper forwardly bent section, two side wings, and a rearwardly bent central section joining all 115 the aforesaid sections; said one-piece second piece comprising a forwardly bent flat section adapted to interlock and hinge with the aforesaid rearwardly bent central section.

3. An advertising device comprising a one 120 piece support; and a one piece second piece; said one piece support comprising a lower forwardly bent section of legends, an upper forwardly bent smaller section of legends, two side wings and a rearwardly bent central section, joining all the aforesaid sections; said one-piece second piece comprising a forwardly bent section of legends, said section having an apparent size midway between the upper and lower sections of 125 130

legends and adapted to be interlocked and hinged with the aforesaid rearwardly bent central section.

4. An advertising device comprising a one

5 piece support; and a one piece second piece; said one piece support comprising a lower forwardly bent section of legends, an upper forwardly bent smaller section of legends, two side wings and a rearwardly 10 bent central section, joining all the aforesaid sections; said one-piece second piece comprising a forwardly bent section of legends, said section having an apparent size midway between the upper and lower sections of 15 legends and adapted to be interlocked and hinged with the aforesaid rearwardly bent central section, and to overlap in forward projection the aforesaid two forwardly bent upper and lower sections.

20 5. An advertising device comprising a one-piece support and a one-piece second piece; said one-piece support comprising a flat piece of material having horizontal slots one above the other the section below the 25 lower slot bent forwardly, the section above the upper slot bent forwardly, the section between the slots bent rearwardly; and side wings; the one piece second piece comprising a forwardly bent piece adapted to interlock with and be hinged to the aforementioned rearwardly bent section.

30 6. An advertising device comprising a one-piece support and a one-piece second piece; said one-piece support comprising a flat piece of material having horizontal slots one above the other the section below the 35 lower slot bent forwardly and formed as a tier of objects, the section above the upper slot bent forwardly and formed as a tier of 40 objects, the section between the slots bent rearwardly; and side wings; the one piece second piece comprising a forwardly bent piece formed as a tier of objects adapted to interlock with and be hinged to the aforementioned rearwardly bent section.

45 7. An advertising device comprising a one-piece support and a one-piece second piece; said one-piece support comprising a flat piece of material having horizontal slots one above the other the section below the 50 lower slot bent forwardly and formed as a tier of objects, the section above the upper

slot bent forwardly and formed as a tier of objects, the section between the slots bent rearwardly; and side wings; the one piece 55 second piece comprising a forwardly bent piece formed as a tier of objects adapted to interlock with and be hinged to the aforementioned rearwardly bent section, and overlap in forward projection both the upper and lower forwardly bent tier forms.

8. An advertising device comprising a one-piece support and a one-piece second piece; said one-piece support comprising a flat piece of material having horizontal slots 60 one above the other, once with a relatively long lower slot and once with a relatively short upper slot, the section below the lower slot bent forwardly, the section above the upper slot bent likewise, the section between 65 the slots bent rearwardly, means for bending as described and side wings with means for bending them into place; the one-piece second piece comprising a forwardly bent piece, with means for so bending, adapted 70 by means of vertical slots in its upper edge to interlock with the aforementioned rearwardly bent section.

9. An advertising device comprising a one-piece support and a one-piece second 80 piece; said one-piece support comprising a flat piece of material having horizontal slots one above the other, once with a relatively long lower slot and once with a relatively short upper slot, the section below the lower slot bent forwardly, the section above the upper slot bent likewise, the section between 85 the slots bent rearwardly and slotted upwardly from its lower edge, means for bending as described, and side wings with means for bending them into place; the one-piece second piece comprising a forwardly bent piece, means for so bending, vertical slots in its top edge adapted to engage the aforementioned slots in the one-piece support and 90 means for overlapping in forward projection portions of the one-piece second piece with the upper and lower forwardly bent sections of the one-piece support.

In testimony whereof, I have signed my 100 name to this specification this 14th day of July, 1924.

GEO. HORNECKER.
